UNITED STATES PATENT OFFICE

GERALD TURNBULL, OF CHICAGO, ILLINOIS

GARMENT AND SUPPORT

Application filed May 18, 1929. Serial No. 364,137.

This invention relates to an improved garment in the form of a shirt equipped with reinforcing means and with supports adapted to support trousers or other garments in position on a person's body with the elimination of the ordinary type of belt and suspenders.

It is an object of this invention to provide a shirt or waist with reinforced portions having connected therewith improved adjustable supporters adapted to have removably engaged thereon elastic connectors which are also adapted to be removably connected to buttons on trousers or skirts to properly support the same in position.

It is also an object of this invention to provide a shirt or similar garment with shoulder looping reinforcements woven in or sewed to the garment and extending to approximately the waist line where slide fastener supports are provided for the removable attachment of elastic connectors adapted to be removably engaged on buttons or the like secured on trousers or similar garments to support the same in position.

It is a further object of this invention to provide an improved shirt with reinforcing sections in which slide fastener slits are provided for the reception of adjustable slides having elastic straps removably engaged thereon and adapted for attachment to the buttons on a pair of trousers to support the trousers in position without the use of a belt or the ordinary type of suspenders.

It is an important object of this invention to provide an improved shirt or upper garment constructed to support a pair of trousers in position with the elimination of the ordinary belt and suspenders by equipping the shirt with reinforced portions having slits therein for the adjustable reception of latchable slides adapted to have elastic straps or connectors buttoned thereto and to buttons on a pair of trousers.

Other and further important objects of this invention will be apparent from the specification and the accompanying drawings.

The invention (in a preferred form) is illustrated in the drawings and hereinafter more fully described.

On the drawings:

Figure 1 is a fragmentary perspective view of an improved shirt embodying the principles of this invention as it might appear supporting a pair of trousers or lower garment on a person.

Figure 2 is an enlarged sectional horizontal view taken on line II—II of Figure 1, with parts omitted.

Figure 3 is an enlarged fragmentary elevational view of a lower portion of the shirt adjacent the upper portion of a pair of trousers illustrating the improved adjustable connecting devices between the shirt and the trousers.

Figure 4 is a fragmentary detail sectional view taken on line IV—IV of Figure 3 and illustrating the released position of the latching plate in dotted lines.

Figure 5 is an elevational or plan view of the sliding support taken on line V—V of Figure 4, with the portion of the shirt omitted.

Figure 6 is an end view of one of the sliding supports taken on line VI—VI of Figure 4.

Figure 7 is an elevational view of one of the elastic connectors or straps used as a connecting means between the trousers and the slide members of the shirt.

As shown on the drawings:

The reference numeral 1 indicates a pair of trousers or lower garment provided with a waist band or hem 2 having four buttons 3 secured on the inner face thereof, two at the front and two in the rear, similar to the arrangement illustrated in Figure 2.

The improved upper garment embodying the principles of this invention in the present instance is illustrated in the form of a shirt 4, the front and back sections of which are reinforced by reinforcing straps or strips 5 which may be formed either by weaving reinforcing strips directly into the material forming the front and back of the shirt or if desired, reinforcing tape or the like may be sewed or otherwise secured in position on the inner side of the front and back of the shirt. The reinforcing strips 5 pass over the shoulder sections of the shirt and extend downwardly at the back and at the front to sub-

stantially the waist line of the shirt or to points slightly above the approximate position of the hip joints of a person wearing the improved shirt.

5 The lower portion of each of the reinforcing strips 5 is provided with a slit or opening 6, the margins of which are equipped with slide fastener strips having teeth or pins 7 with the teeth at one side of the slit or slot 6 offset with respect to those on the opposite side so that when the slit is closed, the slide fastener teeth will be positioned in overlapping relation as clearly illustrated in Figure 3.

13 Associated with each of the slide fastener slots is a slide unit comprising a shoe consisting of flanged tapered outer and inner plates 8 and 9 connected at one end by means of a strap or arm 10. The flanges of the shoe plates 8 and 9 are positioned beyond the outer ends of the slide fastener teeth 7 to coat therewith so that when the shoe is slidably moved in the slot 6, said slot may be either closed or opened depending upon the direction of movement of said shoe. Formed transversely across one end of the top shoe plate 8 is a sleeve 11 which supports a pin 12 on the projecting end of which a pair of hinge sleeves 13 are pivotally mounted. The hinge sleeves 13 are integrally formed in spaced relation at one end of a handle or latch plate 14 having a button 15 secured on the top surface near the outer end thereof. Secured to the bottom of the hinge or latch plate 14 is a curved latch pin 16 which when the latch plate or handle plate 14 is lowered or in a closed position directly above the top shoe plate 8, projects through an aperture or opening 17 provided in the shoe plate 8 permitting the latch pin 16 to extend between two sets of the overlapping teeth 7 as illustrated in Figure 4 to hold the slide unit or shoe locked in a set position of adjustment. It will thus be noted that the button 15 may 45 be located at different elevations or distances from the upper hem or margin 2 of the trousers 1.

With the four slide units locked in predetermined or set positions on the front and back of the shirt 4, the shirt and trousers are now adapted to be connected one to the other by means of four elastic connectors or straps 18, the ends of which are enlarged and are provided with button holes or slots 19 (Figure 7) to permit the upper end of each of the elastic connectors or straps 18 to be engaged on one of the buttons 15 while the lower apertured ends of the connectors or straps are buttoned onto one of the buttons 3 secured on the inner side of the trouser margin 2. The elastic straps or connectors 18 may be readily unbuttoned from either the buttons on the trousers or the buttons 15 on the slide units of the shirt. It will also be understood that 65 the elastic connectors or straps 18 may be re-

placed by new connectors when necessary. The trousers are thus supported by the reinforced shirt and may be lowered or raised depending upon the adjustment of the slide units or shoes coacting with the teeth or pins 7 of the slide fastener strips secured to the margins of the slots 6 provided in the lower portion of the reinforced sections 5 of the shirt.

70 It will of course be understood that many details of construction may be varied through a wide range without departing from the principles of this invention and it is therefore not purposed limiting the patent granted hereon otherwise than necessitated by the 75 scope of the appended claims.

80 I claim as my invention:

1. A trouser supporting shirt having reinforcing strips extending over the shoulders and terminating at substantially the waist line at the front and back of the shirt, said reinforcing strips having slots therein, slide fastener strips secured to the margins of said slots, slide units in said slots coacting with said slide fastener strips, a handle plate pivotally mounted on each of said slide units to facilitate operation thereof, a latch pin on each of said handle plates adapted when the plate is closed to project into latching position between the slide fastener strips to hold 90 the slide unit locked in a set position, buttons mounted on said handle plates, and button-holed elastic connectors removably engaged on the buttons of said handle plates and on the buttons of the pair of trousers to hold the 100 trousers supported in position by the shirt.

2. The combination with a reinforced upper garment having slots therein, of slide fastener strips secured to the margins of said slots, slide units adjustably engaged on said 105 slide fastener strips, handle plates pivotally mounted on said slide units, latch pins secured on said handle plates adapted to coat with said slide fastener strips to hold the slide units locked in set positions of adjustment, buttons on said handle plates, and elastic connectors removably engaged on said buttons and adapted to be removably engaged on buttons carried by a lower garment to support said lower garment in position.

110 In testimony whereof I have hereunto subscribed my name at Chicago, Cook County, Illinois.

GERALD TURNBULL.
